HAIR CUTTING AND SHAPING DEVICE

Raymond E. Lee, Beverly Hills, Calif.

Application July 23, 1948, Serial No. 147,739

Term of patent 14 years

(Cl. D22—3)

To all whom it may concern:

Be it known, that I, Raymond E. Lee, a citizen of the United States of America, residing at 706 N. Walden Drive in the city of Beverly Hills, county of Los Angeles, and State of California, have invented a new, original and ornamental Design for a Hair Cutting and Shaping Device, of which the following is a specification, reference being had to the accompanying drawing, forming part thereof.

In the drawing, Fig. 1 is a plan view of a hair cutting and shaping device, showing my new design;

Fig. 2 is an exploded perspective view;
Fig. 3 is a sectional view taken on line 3—3 of Fig. 1;

Fig. 4 is a sectional view taken on line 4—4 of Fig. 1; and

Fig. 5 is a sectional view taken on line 5—5 of Fig. 1.

I claim:

The ornamental design for a hair cutting and shaping device, as shown.

RAYMOND E. LEE.
